(Cl. D44—15)

Fig. 1.

Fig. 2.

To all whom it may concern:

Be it known that I, Annette Honeywell, a citizen of the United States, residing at Los Angeles, California, have invented a new, original, and ornamental Design for a Plate or Similar Article, of which the following is a specification, reference being had to the accompanying drawings, forming part thereof.

In the drawing

Fig. 1 is a top plan view of a plate, showing my new design; and

Fig. 2 is an edge view of the plate shown in Fig. 1.

The dominant feature of my design is the ornamentation appearing on the article.

I claim:

The ornamental design for a plate or similar article, substantially as shown and described.
